Application April 26, 1933, Serial No. 668,073
 Renewed March 4, 1935

6 Claims. (Cl. 175—359)

My invention relates to inductance coils, and particularly to such coils as are adapted for use in the oscillating circuits of wave meters, standard frequency oscillators, and other services 5 wherein it is desirable or essential that the constants of the circuit remain fixed regardless of variation in temperature or other working conditions.

Among the objects of my invention are: First, 10 to provide an inductance whose variation with temperature is practically nil; second, to provide a coil having a relatively low resistance at radio frequencies; third, to provide a coil which may be cheaply and easily constructed from readily obtainable materials; and fourth, to provide a coil which is rigid and self-supporting.

Other objects of my invention will be apparent 20 or will be specifically pointed out in the description forming a part of this specification, but I do not limit myself to the embodiment of my invention herein described, as various forms may be adopted within the scope of the claims.

Referring to the drawing:

Figure 1 is an elevation, and Figure 2 an end 25 view of an inductor made in accordance with my invention, a portion of Figure 1 being cut away in the drawing to show the construction.

Figure 3 is a top view of one end of the inductor shown in Figure 1.

The inductance of any conductor depends both upon the length of the conductor, upon its cross-section, and particularly upon its disposition relative to other conductors with which it is magnetically linked. The usefulness of an inductor in an oscillating circuit also demands that it have low resistance. It is further desirable that it be compact, not only for purely mechanical reasons, but also to reduce accidental linkages with other circuits. For these reasons it is customary to form inductors as helices or spirals, so that each element of the conductor may be linked magnetically with as many other elements as possible, thus reducing the length and therefore the resistance of conductor required to give a given inductance.

All of the materials having high conductivity have also relatively large coefficients of thermal expansion. A rise in temperature of the coil therefore increases its inductance, not merely in direct proportion to its increase in length, but also by increasing the flux linkages with the other turns of the coil.

Where the inductor is made a portion of an 65 oscillating circuit which must be operated as

nearly as possible at a standard frequency, or one which is used to measure frequency, as in a wave meter, it is necessary that such coils as those described be operated under carefully predetermined thermal conditions, in order that errors due to temperature variations shall not be introduced. In cases where temperature control boxes will not give the required results, i. e., in inductances for radio transmitters of such power that a material amount of heat is generated in the 10 coils themselves, such devices as water-cooling have been introduced to maintain the temperature substantially constant.

Broadly considered, my invention comprises an inductor wherein an insulating core having a 15 substantially zero coefficient of thermal expansion has bonded thereto a plurality of turns of a conductor having a relatively high coefficient of thermal expansion. I prefer to mold or cut a thread in the exterior surface of a pyrex or 20 quartz cylinder, and deposit silver on one face of the thread to form the inductor. The silver, being closely adherent to the core material, cannot greatly change its physical proportions, and its inductive effect, therefore, is but little disturbed by temperature variations.

In the drawing, which illustrates a preferred form of cylindrical inductor, a cylindrical core 1 is provided with an exterior flat-topped thread 2. The core may be molded from "pyrex" or quartz, 30 or other insulating material having a low coefficient of thermal expansion. It is desirable that the threads be molded on the surface, and be an integral part of the core. At the same time, contact extensions 4—4 may be molded at each 35 end of the core cylinder, the outer surface 5 being an extension of the flat top 6 of the thread.

The number of turns, length of cylinder, and diameter is predicated on the amount of inductance desired, while the depth of the thread will 40 depend on the voltage used and length of surface necessary to provide proper guard against surface leakage. These factors, however, are purely matters of design well known in the art, to all of which my invention is adapted. 45

It is desirable, after a proper core has been provided, to polish the flat top 6 of the thread and otherwise prepare it for a silver deposit 7. This deposit may be placed on the thread by any 50 of the chemical deposition methods well known in the art, and need only be thick enough to carry the current necessary for the subsequent plating operation.

The portions of the thread below the exterior 55

surface are not silvered, but on the contrary, are kept free from any conductive material.

Contact is then made to the silver spiral, the core is immersed in a plating bath, and a conductor 5 or 8, preferably silver, is electrically deposited upon the top of the original silver film, until a sufficient strip has been formed to properly carry the current needed for the finished inductor. Plating is then stopped, binding posts 9-9 are 10 inserted in holes 10 in the contact extensions making direct connection to the silver strip, and the inductor is ready for use.

A modified process may be employed which gives the same results. The cylindrical core is 15 not threaded, but the exterior surface is polished and silvered as a whole. The silver is then selectively removed to form a continuous spiral conductor, and electroplated to form the inductor. It is preferable, in this latter case, to cut the core 20 below the exterior surface, while removing the silver. When this is done, the finished inductor is identical with the inductor formed on a molded core as first described.

It has been found that such inductors maintain 25 a remarkably uniform inductive effect in spite of temperature variations, the conductor being firmly held to a substantially non-expanding core cannot itself expand to increase the inductance. The bond between the silver and the core material 30 is sufficiently strong to prevent any tearing loose of the silver, the total physical distortion, therefore, being substantially limited to the distortion of the core.

While the invention is shown as adapted to a 35 cylindrical inductor, it is of course adapted to other forms, such as a flat inductance, the thread being cut on one face of a sheet of core material. It may also be desirable to deposit the conductor on other than the top face of the thread, as for 40 example on a side wall 14 of the square thread

shown. This would give an inductor equivalent to the usual type of inductor using an edgewise wound ribbon.

I claim:

1. An inductor comprising a cylindrical core of 5 an insulating material having a relatively low coefficient of thermal expansion, said core having a thread cut on the exterior surface thereof, a layer of silver chemically deposited on one surface of said thread, and a second layer of silver 10 electrically deposited on said first layer.

2. An inductor comprising a cylindrical quartz core, said core having a thread cut on the exterior surface thereof, a layer of silver chemically deposited on one surface of said thread, and a 15 second layer of silver electrically deposited on said first layer.

3. An inductor comprising a cylindrical pyrex core, said core having a thread cut on the exterior surface thereof, a layer of silver chemically deposited on one surface of said thread, and a second layer of silver 20 electrically deposited on said first layer.

4. An inductor comprising a cylindrical core of insulating material, said core having a thread on 25 the exterior surface thereof, a layer of metal chemically deposited on one surface of said thread, and a second layer of metal electrically deposited on said first layer.

5. An inductor comprising a core of insulating 30 material, a bonding layer of metal chemically deposited on a surface thereof, and an additional layer of metal electrically deposited on said first layer.

6. An inductor comprising a core of insulating 35 material, a relatively thin bonding layer of metal chemically deposited on a surface thereof, and a relatively heavy additional layer of metal electrically deposited on said first layer.
